(57) **CLAIM**

The ornamental design for a wireless charging station, as shown and described.

DESCRIPTION

FIG. 1 is a perspective view of the wireless charging station showing our new design;

FIG. 2 is a front view of the wireless charging station of FIG. 1;

FIG. 3 is a left view of the wireless charging station of FIG. 1;

FIG. 4 is a right view of the wireless charging station of FIG. 1; and,

FIG. 5 is a top view of the wireless charging station of FIG. 1.

The broken lines depict environmental subject matter and form no part of the claimed design. In FIGS. 1 and 5, the broken lines shown on the wireless charging station depict portions of the wireless charging station that form no part of the claimed design.

1 Claim, 5 Drawing Sheets
